(57) **CLAIM**

The ornamental design for a wall sconce, as shown and described.

DESCRIPTION

FIG. 1 is a perspective view of the wall sconce according to the present invention;

FIG. 2 is a front view of the wall sconce shown in FIG. 1; FIG. 3 is a back view of the wall sconce according to the present invention;

FIG. 4 is a left view of the wall sconce according to the present invention;

FIG. 5 is a right view of the wall sconce according to the present invention;

FIG. 6 is a top view of the wall sconce according to the present invention;

FIG. 7 is a bottom view of the wall sconce according to the present invention;

FIG. 8 is a perspective view of another embodiment of the wall sconce according to the present invention;

FIG. 9 is a front view of the wall sconce shown in FIG. 8; FIG. 10 is a back view of the wall sconce according to the second embodiment of present invention;

FIG. 11 is a left view of the wall sconce according to the present invention;

FIG. 12 is a right view of the wall sconce according to the second embodiment of the present invention;

FIG. 13 is a top view of the wall sconce according to the second embodiment of the present invention; and,

FIG. 14 is a bottom view of the wall sconce according to the second embodiment of the present invention.

The broken line showing of portions of the wall sconce is included for the purpose of illustrating environmental structure and forms no part of the claimed design.
